UNITED STATES PATENT OFFICE.

HIRAM STEVENS MAXIM, OF LONDON, ENGLAND.

AUTOMATIC GUN.

SPECIFICATION forming part of Letters Patent No. 447,524, dated March 3, 1891.

Application filed June 10, 1890. Serial No. 354,930. (No model.) Patented in England October 13, 1886, No. 13,083; in Belgium October 15, 1887, No. 79,005; in Italy November 26, 1887, No. 22,500; in France December 14, 1887, No. 185,641; in Austria-Hungary April 21, 1888, No. 34,166, and in Germany August 24, 1888, No. 44,208.

To all whom it may concern:

Be it known that I, HIRAM STEVENS MAXIM, a citizen of the United States, and a resident of London, England, have invented certain new and useful Improvements in Automatic Guns, (for which I have obtained patents in the following countries: in Great Britain, No. 13,083, dated October 13, 1886; in France, No. 185,641, dated December 14, 1887; in Belgium, No. 79,005, dated October 15, 1887; in Germany, No. 44,208, dated August 24, 1888; in Austria-Hungary, No. 34,166, dated April 21, 1888, and in Italy, No. 22,500, dated November 26, 1887,) of which the following is a specification, reference being had to the accompanying drawings.

My present invention relates to means for cooling the barrel of a gun by means of water or other suitable liquid contained in a reservoir arranged above, below, or at one side of the barrel and injected at intervals into a suitable casing around the same. For this purpose I combine with the said casing and reservoir means whereby at each discharge of the gun communication will be established between the said reservoir and casing by the pulling of the trigger or by the movement of the barrel or other part of the gun or in any other convenient manner, so that a small quantity of the water or other liquid may flow under the action of gravity into the said casing or may be forced therein by means of compressed air or by means of a pump, the piston of which consists of an enlargement of the barrel, or which is provided with a separate piston connected with the barrel or other moving part of the gun.

Figures 1 and 2 show in sectional elevation a gun-barrel provided with means, hereinafter described, for cooling the same while the gun is in use for firing. Fig. 3 is a transverse section on the line $x-x'$, Fig. 1. Fig. 4 is a side elevation, partly in vertical central section, showing apparatus for cooling the barrel while the gun is in use for firing. Fig. 5 is a vertical central section of part of the said apparatus, drawn to an enlarged scale. Fig. 6 is a vertical longitudinal central section showing a modification of my invention.

Fig. 7 is a vertical longitudinal central section showing another modification thereof. Fig. 8 is a rear elevation, and Fig. 9 is a transverse section, showing details of construction. Fig. 10 is a vertical longitudinal central section illustrating another modification of my said invention. Fig. 11 is a vertical longitudinal section; Fig. 12, an end elevation showing details of construction. Fig. 13 is a vertical longitudinal central section illustrating a further modification of my said invention. Fig. 14 is a transverse section on the line $x'-x'$, Fig. 13. Fig. 15 is a longitudinal section of the gun shown in Fig. 1 in position on its frame.

Like numerals indicate corresponding parts throughout the drawings.

Referring to the figures, 1 is a casing which is firmly attached to the gun-frame 2 and which surrounds the barrel 3.

4 is a tube which is fixed upon the barrel 70 and slides therewith in the said frame. A pipe or passage 5 extends from the casing 1 to a reservoir 6, Figs. 4 and 7, and is provided with a valve 7. The reservoir 6 is designed to contain water or other suitable liquid for 75 cooling the barrel, and is formed in the gun carriage or mounting, as shown, although without departure from the invention a separate and similarly-connected reservoir may be employed. The valve 7 consists of a rod 80 or spindle having a conical end and extending through a stuffing-box 8. The said valve 7 is connected in any suitable manner with a part of the gun that has a definite movement 85 relatively to the other parts at each discharge of the gun, as hereinafter described, so that it will be opened and closed by the movement of such part.

The reservoir 6, Figs. 4 and 7, has a pipe 9, extending from the top to or nearly to the 90 bottom thereof.

The tube 4 is made with an elongated slot 10, so that there will always be an opening for the flow of the water or other liquid from the pipe or passage 5 into the said tube, notwithstanding the to-and-fro movement of the barrel. To provide for effectually cooling the rear part of the barrel, this tube is made to

extend to the breech end thereof and is closed at its forward end by a ring or annular piece 11, having a small aperture 12 above the barrel, and also, if desired, at each side thereof. Therefore the water which enters the tube 4 must flow around the breech end of the barrel before it can escape from the said tube into the main portion of the casing 1. I prefer, moreover, to provide at suitable intervals along the barrel 3 and casing 1 partitions formed of annular pieces 13, which divide the said casing into compartments, leaving apertures 14 above or at one or both sides of the barrel to permit the flow of the water or other liquid from one to another of the said compartments. These partitions are advantageously constructed, as shown in Figs. 8 and 9—that is to say, a ring or annular piece 15, adapted to fit closely around the barrel, is attached by means of distance-pieces 17 to another ring or annular piece 16, designed to be secured in the casing 1, and of such internal diameter that when secured in the said casing it will not touch the barrel. The distance-pieces 17 keep the said two rings or annular pieces apart and permit the passage of the water or other liquid between them. By means of the above-described partitions the flow of the liquid from the rear to the forward end of the casing 1 is impeded or retarded. Suitable apertures are formed in the forward end of the casing 1 above the barrel for the escape of the water from the said casing.

The reservoir 6 is to be partially filled with water or other suitable liquid, and air is then to be pumped or forced therein until it is compressed to such an extent that by its expansion it will force the liquid out of the reservoir through the pipe 9 into the casing 1 when the valve 7 is opened. Therefore when the trigger is pulled to fire the gun a small quantity of water will be injected into the casing 1 and will pass through the said casing from end to end, thereby effectually cooling the barrel while the gun is in use for firing.

To provide for the introduction of the liquid and the compressed air into the reservoir 6 I insert in the side of the said reservoir a socket or hollow plug 18, provided with a valve 19, which opens inward, and which is held upon its seat by a spring 20. The said socket is, moreover, provided with a screw-cap or plug 21 for tightly closing the same. To charge the reservoir 6 the screw-cap or plug 21 is first, removed, and the nozzle of a supply-pipe is screwed into the said socket 18 until its extremity comes in contact with the outer end of the valve 19 and pushes the said valve away from its seat. The desired quantity of water is then introduced into the said reservoir through this supply-pipe. The said pipe is then removed from the socket 18, and the spring 20 by its reaction closes the valve 19.

Another pipe is then connected with the said socket 18, and air is pumped or otherwise forced into the reservoir 6 until the required

pressure therein is attained, the valve 19 permitting the entrance of the air, but preventing escape thereof.

I prefer to provide means whereby communication between the reservoir 6 and the pipe or passage 5 will be automatically established in the act of placing the gun upon its mounting. For this purpose I employ a device such as that shown in Figs. 4 and 5, in which 22 is a hollow cylinder screwed into the upper end of the reservoir 6. 23 is a piston fitted to slide up and down in the said cylinder and formed or provided with an extension or stem 24, which is fitted to slide in an aperture or passage 25, whereby communication is established between the said cylinder 22 and the reservoir 6.

26 is another piston also fitted to slide up and down in the cylinder 22 above the piston 23. An india-rubber valve 27 is inserted in the upper end of the said cylinder and is firmly secured therein by means of a screw-cap 28. The upper surface of the piston 26 forms a seat for the valve 27, and a spring 29 is arranged between the pistons 23 26 and tends to press the piston 26 upward against the valve 27 and to press the piston 23 downward.

30 is a hollow stem which is screwed into a socket 31, firmly attached to the gun-frame and having the passage 5 formed therein. This socket is adapted to fit upon a casing 32, forming a part of the gun-mounting and surrounding the cylinder 22. The pistons 23 26 have small holes 33 34 formed therein to permit the passage of the water through the said pistons. The stem or extension 24 is, moreover, cut away at 35 in such manner as to form a passage for the liquids from the reservoir 6 into the cylinder 22.

In the act of placing the gun on its mounting the hollow stem 30, which is perforated at its lower end, is pushed through the valve 27 and depresses the piston 26, thus allowing the liquid to pass freely from the reservoir 6 into the passage 5. When the valve 27 is closed, the pressure in the cylinder 22 will be equal to the pressure in the reservoir 6. Therefore the piston 23 will remain at the lower end of its stroke. When, however, the valve 27 is opened, as above described, water will flow from the cylinder 22 into the casing around the barrel more rapidly than it can flow from the reservoir 6 through the hole 33. Consequently the pressure above the piston 23 will be diminished and the said piston will rise, thereby compressing the spring 29 and partially closing or contracting the passage 25. As the pressure above the piston 23 increases, the spring 29 by its reaction moves the said piston downward, thereby again opening the passage 25. The above-described device therefore constitutes a reducing-valve, whereby the flow of water is accurately regulated or controlled, as required.

The reservoir may be of various designs, according to the character of the gun-mounting.

In Fig. 7, for example, it is in the form of an elongated cylinder forming part of a tripod-frame or mounting for the gun.

If a reservoir of cooling-liquid independent of the gun be employed, the connection will be made to it through the nozzle 70, Fig. 15. On the other hand, if the support for the gun be itself or contain the reservoir, as in Figs. 4, 5, and 7, the frame of the gun 2 is securely connected with the socket 31 of Fig. 5 by the trunnions 71. One of them is hollow and forms a part or continuation of the passage 5, the joints about the trunnions being closed by a packing 72, held in place by a stout spiral spring 73, contained in a chamber in the casting forming the upper part of the socket and closed by a screw-cap 74.

In some instances I provide means whereby the opening or openings for the passage of the water may be increased or diminished at will to regulate the speed of firing, as hereinafter described.

In Figs. 10, 11, and 12 I have shown a pump and devices whereby the same will be operated in the to-and-fro movement of the barrel to draw liquid from a tank or reservoir and force it into the casing 1 around the barrel. The breech end of the barrel 3 is fitted into a cylinder 36 at the rear of the casing 1, and a piston-ring or packing-ring 37 is fitted in a groove in the said barrel. The cylinder 36 is connected with the said tank or reservoir by means of a pipe or passage 38, provided with a check-valve 39, and with the casing 1 by means of a pipe or passage 40, provided with a check-valve 41. A sliding rod 42 is so arranged, in combination with the valve 39, that when the barrel after its recoil returns to the firing position a projection thereon (shown in dotted lines in Fig. 10 and marked 64) will push forward the said sliding rod 42 and open the valve 39. The barrel in its recoil will draw liquid from the tank or reservoir through the said valve into the cylinder 36 and will in its forward or return movement deliver the said liquid through the valve 41 into the casing 1.

To provide for regulating the speed of firing, I sometimes make the valve 41 with a screw-threaded spindle 43, extending through a stuffing-box 44 and provided with a screw-nut 45, by turning which in one or the other direction the lift of the said valve may be increased or diminished and the velocity of the forward or return movement of the barrel thus regulated.

In the modification of my invention shown in Figs. 13 and 14 a plunger 46 is fixed in a bracket 47, formed on or attached to the barrel 3 and extending downward therefrom. This plunger works in a cylinder 36, connected with the water tank or reservoir by means of a pipe or passage 38, provided with a check-valve 39, and with the casing 1 by means of a pipe or passage 40, provided with a check-valve 41. The two ends of the said cylinder are, moreover, connected by means of a pipe

or passage 51, the flow of liquid through which may be regulated by means of a rod or plunger 52, which is curved at its forward end, as shown, (or may be inclined, if desired,) and which works in a stuffing-box 53 at the rear end of the said pipe or passage 51. This rod or plunger is acted upon by a spring 54, which tends to pull it outward. It is connected by means of a rod or bar 55 with a lever 56, pivoted at 57 to the rear end of the frame 2, a pin or stud 58 being fixed in one arm of the said lever and working in a slot 59 in the said rod or bar 55. The other arm of the said lever 56 is coupled to a screw-threaded rod 60, extending through the rear end of the frame 2 and provided with an adjusting-nut 61. By turning this nut in one or the other direction the position of the forward end of the plunger 52 relatively to the part 62 of the passage 51 may be altered, so as to increase or diminish the opening for the flow of liquid from one to the other end of the cylinder 36.

The plunger 46 is provided with a perforated piston 48, held against a flange or collar 49 on the plunger 46 by means of a spring 50.

The forward part of the cylinder 36 is of considerably greater diameter than the piston 48. The rear part of the said cylinder is, however, of such diameter that the piston will fit and slide therein.

The operation of the device above described is as follows—that is to say, assuming the parts to be in the firing position, as shown, and the whole of the available space in the cylinder 36 and passage 51 to be filled or nearly filled with liquid, in the recoil the plunger 46 will be partially withdrawn from the said cylinder, and more liquid will thus be drawn into the said cylinder from the tank or reservoir. As soon as the piston 48 reaches the smaller part of the cylinder 36 the liquid behind the piston will flow through the passage 51 into the space in front of the said piston; or should the said passage be nearly closed by the plunger 52 the spring 50 will be compressed and the liquid will flow through the perforated piston 48. In the forward or return movement of the barrel the plunger 46 will be forced into the cylinder 36. The holes in the piston 48 will be closed by the flange or collar 49, so that while the said piston is in the smaller part of the cylinder the liquid in front of the piston must flow through the passage 51 into the space behind the piston. The velocity of the forward or return movement of the barrel, and consequently the speed of firing, will therefore depend upon the extent of opening of the part 62 of the said passage. The plunger 46, as it is pushed into the cylinder 36, displaces some of the liquid therefrom and forces the same into the casing 1 for the purpose of cooling the barrel, as above specified.

It will be seen from the foregoing description that the speed of firing can be very accurately regulated or determined by adjusting the nut 61.

The general form of the gun or casing is illustrated in Fig. 15. To the trigger 67 in this gun is pivoted a rod 69, which passes forward through the rear wall of the gun-casing. The end of said rod is provided with a suitable head 68, which is normally thrown forward by a spiral spring 63, surrounding the rod 69. To this rod, or any equivalent therefor the valve mechanism 7, Figs. 1 and 6, is or may be connected and the necessary movement imparted thereto by the movements of the trigger.

Having now particularly described and ascertained the nature of my invention and in what manner the same is to be performed, I declare that what I claim is—

1. In a machine-gun, the combination, with the barrel, the breech mechanism, and a part

movable by or in the operation of the gun, of a casing or chamber surrounding the barrel and provided with an inlet and an outlet, a reservoir of water or cooling liquid connecting with the said chamber, and a valve intermediate to the reservoir and chamber for controlling the communication between the same, said valve being connected with and controlled by the said movable part, as set forth.

2. In a machine-gun, the combination, with the barrel, the breech mechanism, and a part

movable by or in the operation of the gun, of a casing or chamber surrounding the barrel and provided with an inlet and an outlet, a reservoir of water or cooling liquid under pressure connecting with the said chamber, and a valve intermediate to the reservoir and chamber for controlling the communication between the same, said valve being connected with and controlled by the said movable part, as set forth.

3. The combination, in a gun, with a chamber or casing surrounding the barrel and provided with an inlet and an outlet, of a reservoir or receptacle containing water or cooling liquid and formed or attached to the gun carriage or mounting and connected with the

chamber, and a valve for controlling or effecting the flow of water from said reservoir into the chamber surrounding the barrel and dependent for operation upon the movement of a part of the gun, as set forth.

4. The combination, in a gun, with a chamber or casing surrounding the barrel and pro-

vided with an inlet and an outlet, of a reservoir of liquid communicating therewith, and a valve for controlling the flow of liquid from the reservoir to the chamber surrounding the barrel connecting or engaging with the trigger, whereby said valve will be opened by the movement of the trigger in discharging the gun, as set forth.

5. The combination, in a gun, with a chamber or casing surrounding the barrel, of an air-tight reservoir containing a cooling fluid and compressed air, a passage of communication between the reservoir and the said chamber, a valve contained therein, and connection between the same and the trigger or equivalent moving part of the gun, as set forth.

6. The combination, with a gun having a chamber or casing surrounding the barrel and provided with an inlet port or passage, of a reservoir containing a cooling fluid and a self-closing or automatic outlet-valve for said reservoir, adapted to be freed and held open by the inlet-port of the casing around the barrel when the said casing and reservoir are brought into communication, as set forth.

7. In a gun, the combination, with a chamber or casing surrounding the barrel, of a reservoir containing a cooling fluid, means for opening and closing communication between the reservoir and the casing, and an automatic reducing-valve for regulating the flow of liquid when such communication is established, as set forth.

8. The combination, with a gun-barrel, a chamber or casing surrounding the same, and a hollow perforated stem forming the inlet-port for such chamber, of a reservoir for containing a cooling liquid, an india-rubber valve-seat surrounding the outlet of such reservoir, and a spring-impelled valve for closing the outlet and adapted to be forced off its seat and opened by the tubular stem when the gun and reservoir are associated, in the manner described.

In testimony whereof I have hereunto signed my name in the presence of two subscribing witnesses.

HIRAM STEVENS MAXIM.
